UNITED STATES PATENT OFFICE.

GEORGE ALTIMARE AND JOHN LOVELL, OF PARSONS, KANSAS.

BOILER WATER-JACKET.

1,184,504.

Specification of Letters Patent. Patented May 23, 1916.

Application filed July 28, 1915. Serial No. 42,282.

To all whom it may concern:

Be it known that we, GEORGE ALTIMARE and JOHN LOVELL, both citizens of the United States, and residents of Parsons, in the county of Labette and State of Kansas, have invented a new and Improved Boiler Water-Jacket, of which the following is a full, clear, and exact description.

The invention relates to steam boilers and its object is to provide a new and improved water jacket for such boilers to prevent cold drafts from reaching the flues and flue sheet with a view to prevent leakage due to sediment, expansion, and contraction.

In order to accomplish the desired result, use is made of a casing fitting onto the face of the flue sheet and having thimbles extending therethrough, the inner ends of the thimbles registering with the boiler flues, the said casing being connected by inlet and outlet pipes with the water space of the boiler to cause the water to circulate through the casing.

A practical embodiment of the invention is represented in the accompanying drawings forming a part of this specification, in which similar characters of reference indicate corresponding parts in all the views.

Figure 1 is a longitudinal central section 30 of the water jacket as applied to a steam boiler, the section being on the line 1—1 of Fig. 2; Fig. 2 is a cross section of the same on the line 2—2 of Fig. 1; and Fig. 3 is an enlarged longitudinal section of a portion 35 of the water jacket as applied.

The casing A of the water jacket is preferably made of malleable iron or steel and fits onto the face of the flue sheet B of a boiler C of usual construction and having, as shown, small flues D and larger super-heating flues D'. The casing A is fastened by stud bolts E or like fastening devices, to the flue sheet B, the stud bolts passing through suitable holes F formed in the casing A, as plainly indicated in Fig. 3. The casing A is provided with integral thimbles G extending from the face of the casing to a distance beyond the back thereof, the projecting ends G' fitting snugly into the corresponding flues D and D'. The casing A is connected near its upper end by a circulating pipe H with the crown sheet I of the boiler C and an outlet pipe J connects the lower end of the casing A with the water leg K of the boiler C. Thus by the arrangement described, the interior of the

casing A is connected at its upper and lower end with the water space of the boiler C to allow the water to circulate through the said casing A. It will be noticed that the 60 casing A covers the entire surface of the flue sheet B and consequently protects the said flue sheet against direct drafts, and the thimbles G protect the entrance ends of the flues D and D' against said drafts to 65 prevent cracking of the flue sheet and leakage of the flues.

In order to permit of conveniently cleaning the casing A of any sediment that may accumulate therein, use is made of cleaning-out sleeves L arranged at the sides of the casing A and access to which is had by plugs N screwing in the shell of the boiler directly opposite the sleeves L, as will be readily understood by reference to Fig. 2. 70 Thus when it is desired to clean out the casing A, the plugs N are removed to permit the introduction of a wash-out hose connected with a suitable water supply. The wash water passes by way of the pipe J 80 into the leg of the boiler, from which the sediment is removed in the usual manner. After the casing has been washed out the plugs N are again placed in position.

Having thus described our invention, we 85 claim as new and desire to secure by Letters Patent:—

1. A water jacket for steam boilers, comprising a casing constructed to fit throughout its entire extent against the flue sheet of 90 a boiler, and provided with pipes extending from its upper and lower portions for connection with the crown sheet and water leg of the boiler respectively, and with thimbles extending therethrough, the inner ends of 95 the thimbles projecting beyond the inner face of the casing and adapted to fit in the boiler flues.

2. The combination with a boiler having a flue sheet, flues, a crown sheet and a water leg, of a casing having its inner face fitting throughout its entire extent against the face of the said flue sheet and having integral thimbles extending from the face of the casing through the casing and a distance 100 beyond the back of the casing, the projecting ends of the thimbles fitting into the said flues, and inlet and outlet pipes connecting the said casing with the said crown sheet and the said water leg.

3. The combination with a boiler having a flue sheet, flues, a crown sheet and a water

leg, of a casing having its inner face fitting throughout its entire extent against the face of the said flue sheet and having integral thimbles extending from the face of the casing, through the casing and a distance beyond the back of the casing, the projecting ends of the thimbles fitting into the said flues, inlet and outlet pipes connecting the said casing with the said crown sheet and the said water leg, wash-out sleeves at the

sides of the casing and plugs at the sides of the boiler opposite the sleeves.

In testimony whereof we have signed our names to this specification in the presence of two subscribing witnesses.

GEORGE ALTIMARE.

JOHN LOVELL.
